FRANK C. ANDERSON, OF CINCINNATI, OHIO.

SWITCH STAND.

1,407,454.

Specification of Letters Patent. Patented Feb. 21, 1922.

Application filed October 27, 1921. Serial No. 510,847.

To all whom it may concern:

Be it known that I, FRANK C. ANDERSON, a citizen of the United States, residing at Cincinnati, in the county of Hamilton and 5 State of Ohio, have invented certain new and useful Improvements in Switch Stands, of which the following is a specification.

My invention relates to ground-lever parallel-throw switch-stands in general, and 10 more particularly to the kind disclosed and claimed in my Patents No. 1,360,862, dated November 30, 1920, and No. 1,389,730, dated September 6, 1921, upon which the present invention is an improvement.

15 Its object, like the switch-stands of those patents, is to combine ease of manual switch-throwing operation with control of the point-rails by a weighted handle, to permit normal operation without excessive vibration or opening of the point-rails, but to 20 permit opening if the switch is run through, without resilient or breakable connections. It is the especial object of the present invention to increase the efficiency of my 25 switch-stand in the performance of those functions. Other objects, peculiar to the present invention, as well as in common with those of the just mentioned patents, will appear in the course of the ensuing description.

30 I attain these objects by the device illustrated, for example, in the accompanying drawing, in which—

Figure 1 is a sectional plan view of the 35 switch-stand, the section being on the plane of the line 1—1 of Fig. 2;

Fig. 2 is a sectional front elevation, the section being on the plane of the line 2—2 of Fig. 1;

40 Fig. 3 is a vertical front-to-rear section on the plane of the line 3—3 of Fig. 1;

Fig. 4 is a perspective detail view of the rack member;

45 Fig. 5 is a similar view of the pinion member;

Fig. 6 is a partial section corresponding to Fig. 2, showing a modification of part of the rack member guide; and

50 Fig. 7 is a partial vertical cross-section on the plane of the line 7—7 of Fig. 6.

The base of the stand comprises the middle part 1 with feet 2 at opposite ends, extending down to the foot-plates 3, and comprises the front shaft bearing 4 and the

55 segmental extension 5 at the rear, with the crank-and-clutch bearing opening 6 down through the extension 5, concentric therewith and in front-to-rear alinement with the bearing 4. Just to the rear of this bearing 4 the base has the depression 7, and has the 60 two front pedestals 8 at opposite sides of the rear end of the bearing 4, and the rear pedestal 9, running entirely across; these pedestals merging, at their bottoms, into the front and rear walls, respectively, of the depression 7.

The casing comprises the front shaft bearing 10, rear extension with the target-shaft-bearing opening 11, flat top 12, and open bottom, permitting it to be placed down over 70 the interior working parts after the latter have been fully assembled on the base, and to be bolted to the base by means of the front bolts 13 in ears at opposite sides of the front bearings 4 and 10, and rear bolts 75 13' near respective rear corners of the base middle part 1.

The casing, and the base, and numerous details thereof, are similar to those of said 80 patents, varying therefrom somewhat in the dimensions and proportions, and being claimed therein, but are fully disclosed herein to elucidate the present disclosure. The handle-lever 14, with the weight handle 15 of approved design at one end, and with the 85 pinion shaft 16 at its other end, preferably forged integrally therewith, also is similar to those of said patents, with the shaft 16 lying in the front shaft bearings 4 and 10 and extending back across the depression 7. 90

In the present invention, however, the pinion member 17 is not a segment of a circular gear, but is substantially one half of an elliptical gear lying at the opposite sides of the major axis of the ellipse, which major 95 axis is alined with the handle-lever 14. It preferably has slightly extended hubs 18 at opposite ends, and fits on the shaft 16, within the depression 7, with its hubs bearing against the front and rear walls of this 100 depression, and being held in its described position on said shaft 16 by a pin 19 passing through its central part and through the shaft; the narrower part of the ellipse being recessed to receive one of the ends of this 105 pin 19 and allow it to be headed therein as well as at its opposite end, at the opposite end of the pinion member. In the middle of

the recess is a web 17' to reinforce this part of the pinion member, (Fig. 5.) The teeth of this half-elliptical segmental pinion are disposed along its pitch line at right angles to tangents thereof at the respective tooth locations, according to the principles of elliptical gear design; being as here shown, so arranged that the middle tooth of the series is on the major axis, with five teeth symmetrically arranged around therefrom in both directions, with the last of the five close to the minor axis. Succeeding this fifth tooth at each side, is an additional tooth or lug, preferably somewhat heavier than the other teeth, and merging into the untoothed opposite end or heel of the pinion member, which conforms approximately to the circular hubs 18 thereof. To further reinforce the fastening of the pinion member 17 to the shaft 16, a round key 17" is fitted in suitable keyways bored in the shaft and pinion member, along the shaft.

The rack member 20 comprises the flat body 21 with the downward extensions 22 extending from its middle toward both ends, being highest at the middle and lowest at the ends, and intermediate of these points being curved so that the twelve downwardly projected teeth across the lower faces of these parts follow a pitch line that is a development of a half revolution of the pinion member 17 from one horizontal position of its major axis to the other. These extensions 22 are somewhat narrower than the space between the front and rear pedestals 8 and 9, and the flat body 21 is wide enough to bear on these pedestals with the extensions 22 therebetween; the height of these pedestals being such that the rack and pinion teeth mesh with the terminal tooth of the rack between the last two teeth, one of which is the heavy one before described, at the upper side of the pinion member projecting under the rack member, at which time the rack member will be at its extreme position at one end of the switch-stand. Thus, rotation of the pinion member through 180° will throw the rack member to its extreme opposite position at the opposite end of the switch-stand. Vertical ribs 23 lengthwise of the middle of the rack member join the flat body 21 to the extensions 22. Guide-lugs 24 extend forwardly and rearwardly slightly past the front and rear of the extensions 22, on the lower side of the body 21, the ends of these lugs contacting with the pedestals 8 and 9; and, preferably, slight bosses 25 are formed on the front and rear edges of the extensions 22 to contact with the pedestals 8 and 9 lower down. These lugs 24 and bosses 25 thus guide the rack member laterally. They are located far enough inward from the respective ends of the rack member to make these contacts with the short front pedestals 8 when the mem-

ber is at either extreme position. On the top of the body 21, near opposite ends, in the middle thereof, guide-lugs 26 extend up, to contact with the flat under side of the casing top 12, thus limiting the rise of the rack member from its guideways on the tops of the pedestals 8 and 9 under the slight tilting action of the intermeshing gear parts. In the modification of Figs. 6 and 7, each lug 26 has a pair of small rollers 26', one at each side, on a transverse pin 26" passing through the lug 26; these rollers bearing against the casing top with less friction than merely the upper end of the lug 26. Also on top of the body 21 are the front-to-rear upstanding jaws 27, parallel and considerably spaced apart equidistant from the front-to-rear median line of the body, in either example.

The target-shaft 28 will be understood to be of suitable design in its upper part, to support a target or lamp or other means at any required height; and its lower end is threaded, and it has through it, short distances up from the lower end, two transverse openings. The intermediate crank 29 comprises the hub 30 down through which the target shaft 28 fits snugly; and the arm of the crank has on its front end the head 31, projecting down therefrom in cylindrical shape, with an easy fit between the upstanding jaws 27 of the rack member, while the target shaft 28 extends up through and bears in the opening 11 in the casing and the lower part of the hub 30 extends down into and bears in the base opening 6. The lower end of the hub 30 is grooved transversely, and up a proper distance has the annular flange 32 that rests on the floor of the base around the opening 6, supporting the crank at the proper height to work easily with the rack member; while the target shaft 28 is supported in this crank by pins 33 slipped through openings in the hub registering with the before mentioned target-shaft openings, and retained therein by the rear inner concave wall of the segmental extension of the casing.

The direct switch-throwing crank 34 has a hub part extending up into the opening 6, with a central threaded opening receiving the threaded lower end of the target shaft 28, and with clutch teeth 35 at opposite sides entering the transverse groove of the bottom of the hub 30 of the intermediate crank. The crank arm 36 is adjustable radially in the hub part, to vary the throw of the crank for different switches or to compensate for wear in the switch connections; and connects to the switch-connecting rod 37 by a pin 38, which is prevented from rising by a flat rear extension 39 on the bottom of the rear of the base, and by flanges 40 extended down from the bottom of the base, thereunder, except at an intermediate position, where it is inserted or removed through a 130

slot 41 in the extension 39 at either side of the middle, depending upon which side the crank swings to. This crank construction is fully disclosed and claimed in my second 5 mentioned patent; and the intermediate crank and direct-switch-throwing crank connection is disclosed and claimed in my first mentioned patent, as are the rack, pinion and intermediate crank combination generally, and the construction of the base and 10 casing as described herein.

My present switch-stand has the intermediate crank of such length that considerable 15 space is left between its hub 30 and the rear pedestal 9; and in this space a small box-like depression 42 is formed in the floor of the base, extending from the back of the rear pedestal 9 back under the flange 32 of the hub 30. The rear end of the handle-lever pinion shaft 16 has a central bore, registering with a bore through the pedestal 9; and a pin 43, short enough to assume a horizontal position in the depression 42, is slipped forwardly from that position, 20 through the pedestal bore into the shaft bore, with a square head 44 against the back of the pedestal 9 and lying a slight distance up from the bottom of the depression 42. A lock-plate 45 has its front end inserted under 25 the head 44 and inclines up and back against the rear end of the depression 42, where it will be held down by the flange 32 of the crank 29 when this crank is placed in operative position.

Such a rear bearing for the pinion shaft is disclosed and claimed broadly in my co-pending application Serial No. 486,166, filed July 20, 1921. The described intermediate-crank head 31 is claimed in my co-pending 40 application Serial No. 477,228, filed June 13, 1921.

As in all of my prior patents and applications mentioned, the base has its foot-plates 3 extended forward, with lever-rests 14' 45 thereon, receiving the handle-lever 14 at either end of a throw of 180°; and these foot-plates have openings 3' reducing their cross-sections close to the front edge of the middle part 1 of the base, so they may readily be 50 cut away to make room for latches if the stand is used where these are necessary, as for main-line use. In yards, latches are not necessary, and are undesirable, owing to the frequent throwing necessary. Switches on 55 main lines are not frequently run through in the wrong direction; but in yards this is a very frequent and practically unavoidable occurrence, and it is in yards that my invention is most useful. Elimination of the 60 latches dispenses with the expense and uncertainty of breakable or resilient connections to yield under abnormal strain; but it is necessary to provide against excessive point-rail vibration under normal traffic in the 65 absence of the latch.

In the usual parallel-throw stand, the ratio between the effective radius of the element that corresponds to my intermediate crank and the radius of the pinion member is the controlling factor in calculating the 70 resistance of the handle-lever weight to the rail vibration. The handle-lever length or weight can be varied only within very narrow limits, to be convenient for the switch-man and not to impart too heavy blows to 75 the rests when thrown over.

With the well known gear-and-pinion stands, the pinion radius must be just one-half the radius of the segment-gear radius, to turn the latter 90° with 180° turn of the 80 pinion. In my prior stands mentioned, using a rack with a pinion of uniform radius, and an intermediate crank, the pinion radius may be reduced to about forty-six one-hundredths of the intermediate-crank 85 radius, adding nearly 10% advantage to the handle-lever weight over the pressure on the rails, as compared with the gear-and-pinion stands.

My present invention takes advantage of 90 the circumstance that the added advantage for the weight is needed only at the ends of the throw, and the ratio is unimportant in the intermediate parts of the throw. Thus, the radius of the pinion may increase from 95 both ends toward the middle of the throw sufficiently to provide the added rack throw for swinging through 90° an intermediate crank of radius increased enough to provide, in its ratio to the minimum pinion radius, 100 the needed added advantage for the weight at either end of the throw to effectively resist the vibration of the rails under normal traffic. Thus the ratio of pinion radius to intermediate-crank radius is no longer fixed; 105 and the pinion may have its minimum radius as small as is consistent with proper fastening to its shaft, and the intermediate crank may have its radius as large as is consistent with commercially practical dimensions of 110 the switch-stand, the maximum radius of the pinion being increased accordingly.

In the example herein illustrated, the maximum radius is to the minimum radius of the pinion as seven to three, which affords 115 a rack throw of very nearly five times the minimum pinion radius and permits the intermediate-crank radius to be increased so that the minimum pinion radius, at either end of the throw, is very nearly two-sevenths 120 of the intermediate-crank radius, and the intermediate-crank radius is about one and one-half that of the switch-throwing crank at the indicated adjustment of the latter. This adds about 75% to the weight advantage 125 as compared with the gear-and-pinion stands, and about 60% as compared with my stands of the prior patents and applications mentioned, i. e., it is equivalent to increasing the weight of the handle, or increasing 130

the length of the handle-lever, in those stands, by the percentages indicated, but without actually increasing either of these in my present invention.

Although the leverage at the middle of the throw in the present invention is greatly decreased from that at the ends, the actual increase in length of the intermediate crank so far offsets this that the average total resistance throughout the throw is less than the uniform resistance to the switchman's effort in the prior stands. For instance, averaging the ratios at the several teeth of the pinion, the resultant average ratio is nearly 25% greater than the uniform ratio of the uniform-radius pinion, and, conversely, the switchman's effort to throw a given switch is nearly 20% less. This does not include the additional advantage that when the weight is being lifted, in the first part of the throw, the leverage is greater, and the decreased leverage occurs only as the lever approaches vertical position, increasingly relieving the switchman of the effort of lifting the weight which thus is being more and more supported by the lever itself.

Also, in running through the switch the wrong way, the ratio is high as to this reverse operation of lifting the weight, starting it up rapidly under the heavy force of the rolling stock thus forcing the rails over; and the weight thus acquires heavy momentum to pass completely over and completely throw the switch, with increasing advantage over the rails in its terminal stage of travel. The wheel flanges push the rails only partly over in such an occurrence, especially if they pass through rather slowly; and my present invention better insures complete throwing of the switch, by momentum, than with a uniform-radius pinion. In any device depending upon springs for complete throwing in such cases, weakening of the spring results in incomplete throwing, and breakage of the spring leaves the stand inoperative in that respect, as is also the case with a breakable pin; and neglect to repair the stand may result in a serious accident. My present switch-stand can throw over freely when the switch is run through in the wrong direction, without breakage or dependence upon springs of any kind, and when closed adequately resists vibration of the rails under normal traffic, and the normal manual throwing demands less effort from the switchman.

With the greatly increased length of the intermediate crank, its hub is spaced back from the rear shaft-bearing pin, and the long overhang of the crank unfits it for holding the rack member down on the pedestals; the stand thus differing in these respects from that of my first mentioned application, No. 486,166. I provide for these differences

herein by the locking element 45 between the pin and the crank-hub, and by allowing the flange 32 of that hub to ride thereover as described; and by the upstanding guiding means 26 on the rack, against the fixed casing top as described, or by the modified means with the rollers 26' acting in a similar manner as set forth herein.

It will be understood that any of the parts may have their design or dimensions varied, or have equivalents substituted therefor, as may be expedient under varying conditions. Therefore, while certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

1. In a switch-stand, a base comprising a front-to-rear shaft bearing at its front and a depression to the rear of said bearing, a pedestal to the rear of said depression, a second depression to the rear of said pedestal, a lever with a shaft in said bearing, a substantially semi-elliptical pinion fixed on said shaft and lying within the first mentioned depression, a rear bearing pin in said pedestal and extending into said shaft, a lock-plate in said second depression to contact with the rear part of said pin, and inclining rearwardly and upwardly against the rear end of said depression, a rack member sliding on said pedestal with extensions inclining down in opposite directions from its middle and having teeth on their inclined bottoms meshing downwardly with said pinion, the major axis of the ellipse of said pinion being substantially alined with said lever and the end teeth of said pinion being substantially near the minor axis of said ellipse and meshing with the lower end parts of said rack member at opposite ends of its throw, a crank turning in said base on an upright axis, to the rear of said second depression, engaging with said rack member and having a flange over the rear upper end of said lock-plate, a top element fixed on said base over said rack member and said crank, and an upwardly extended guiding element on said rack member to bear upward on said top element, thereby holding said rack member down on said pedestal, and means for operatively connecting said crank to a switch.

2. In a switch-stand, mechanism comprising a lever and a variable-radius spur pinion coaxially connected, a rack meshing with said pinion, an intermediate crank operatively engaging with said rack, a direct

switch-throwing crank coaxially connected with said intermediate crank, and means operatively supporting said mechanism.

3. In a switch-stand, mechanism comprising a lever and a substantially semi-elliptical spur pinion coaxially connected, a rack meshing with said pinion, an intermediate crank operatively engaging with said rack, a direct switch-throwing crank coaxially connected with said intermediate crank, and means operatively supporting said mechanism.

4. In a switch-stand, mechanism comprising a lever and a variable-radius spur pinion coaxially connected, with a greater pinion radius alined with said lever and lesser pinion radii at opposite sides of said greater radius, a rack meshing with said pinion, an intermediate crank operatively engaging with said rack, a direct switch-throwing crank coaxially connected with said intermediate crank, and means operatively supporting said mechanism.

5. In a switch-stand, mechanism comprising a lever and a substantially semi-elliptical spur pinion coaxially connected, with the major axis of the pinion ellipse substantially alined with said lever and median to the semi-elliptical extent of the pinion, a rack meshing with said pinion, an intermediate crank operatively engaging with said rack, a direct switch-throwing crank coaxially connected with said intermediate crank, and means operatively supporting said mechanism.

6. In a switch-stand, mechanism comprising a lever and a variable-radius spur pinion coaxially connected, a rack member above and meshing with said pinion, an intermediate crank operatively engaging with said rack member thereabove, a direct switch-throwing crank coaxially connected with said intermediate crank, a base forming bearing and supporting means for said mechanism and having an opening through which said intermediate crank and said direct switch-throwing crank are connected, a substantially flat-topped open-bottomed casing fitting on said base over and around said mechanism, and an upward extension on said rack member to bear up against the under side of said flat top of said casing.

7. In a switch-stand, supporting means, a suitable rack member and a lever operatively mounted on said means, a variable-radius spur pinion coaxially connected to said lever and meshing with the teeth of said rack, an intermediate crank directly engaging with said rack member and having a bearing in said supporting means, and a direct switch-throwing crank coaxially connected with said intermediate crank and offset downwardly therefrom.

8. In a switch-stand, supporting means, mechanism operatively supported by said

means, comprising a lever and a variable-radius spur pinion coaxially connected, a rack member having teeth meshing with said pinion, an intermediate crank in direct engagement with said rack member, and a direct switch-throwing crank coaxially connected with said intermediate crank and extending below the lowest part of said supporting means for connection to switch-connecting means therebelow.

75

9. In a switch-stand, mechanism comprising a lever and a substantially semi-elliptical spur pinion connected with the major axis of the pinion ellipse substantially alined with said lever, a rack member above said pinion and having extensions on its bottom inclining down in opposite directions from its middle part with teeth on their bottoms meshing with said pinion, the terminal teeth of said pinion being near the minor axis of the pinion ellipse and meshing with respective terminal teeth of the rack member at opposite ends of the throw thereof, an intermediate crank operatively engaging with said rack member, a direct switch-throwing crank coaxially connected with said intermediate crank, and means operatively supporting said mechanism.

80

10. In a switch-stand, a base comprising a front-to-rear shaft bearing at its front, and a pedestal extending up to the rear of said bearing, and having an opening down through it back of said pedestal and a depression between said opening and said pedestal, in front-to-rear alinement with said shaft-bearing.

95

11. In a switch-stand, a rack member comprising a substantially straight guiding part, and extensions inclining away from said part in both directions from near the middle thereof and having teeth on their adjacent sides.

105

12. In a switch-stand, a rack member having a series of teeth arranged to mesh with a variable-radius pinion rotating around a fixed axis while said rack member travels in a substantially straight path.

110

13. In a switch-stand, a rack member having a series of teeth curving away from a middle point of said member in both directions and arranged to mesh with a substantially semi-elliptical pinion rotating around a fixed axis with its teeth disposed on both sides of the major axis of the ellipse while said rack member travels in a substantially straight path from a meshing with said pinion substantially at one end of the minor axis to a meshing therewith substantially at the other end of said axis.

115

14. In a switch-stand, a rack member comprising a main substantially straight guiding part with extensions inclining away from one side in opposite directions from its middle point and having teeth on their adjacent sides, said member having longitu-

120

125

130

dinal bearing surfaces along opposite edges of said extensions on this side of said main part.

15. In a switch-stand, a rack member comprising a main substantially straight guiding part with extensions inclining away from one side in opposite directions from its middle point and having teeth on their adjacent sides, and longitudinal median ribs 10 connecting remote parts of the respective extensions to said main part.

16. In a switch-stand, a rack member having a series of teeth arranged to mesh with a variable-radius pinion rotating around a 15 fixed axis while said rack member travels in a substantially straight path, and having guiding means extending therefrom in a direction opposite to that of the extension of said teeth.

20 17. In a switch-stand, a rack member having teeth extending from one side and a guiding extension on its opposite side.

18. In a switch-stand, a rack member having teeth extending from one side and longitudinally spaced guiding extensions on its 25 opposite side.

19. In a switch-stand, a base having a rack support, a rack on said support, operative engaging means on said rack extending 30 away from said support, guiding means on said rack extending past said engaging means, and means fixed on said base and engaging said guiding means to hold said rack toward said support.

35 20. In a switch-stand, a support, manipulating means, switch-connecting means, a toothed member operatively connected with said manipulating means, and a toothed member operatively connected with said 40 switch-connecting means, said members meshing together and both of said members having their teeth arranged in non-circular series.

21. In a switch-stand, a support, manipulating means, switch-connecting means, a toothed member operatively connected with said manipulating means, and a toothed member operatively connected with said 45 switch-connecting means, said members meshing together, and one of said members being rotary and having part of its teeth farther from its center of rotation than others of its teeth.

22. In a switch-stand, a base comprising a 55 front-to-rear shaft bearing at its front, a lever with a shaft in said bearing, a pinion fixed on said shaft to the rear of said bearing, a bearing pin mounted on said base and projecting into said shaft, to the rear of said pinion, a locking element on said base behind said pin, and means on said base retaining said locking element.

23. In a switch-stand, a switch-throwing 60 pinion, bearings for said pinion at both ends of said pinion, one of said bearings being

removable, locking means for this bearing, and switch-connecting means in operative relation to said pinion and extending against and retaining said locking means in locking relation to said removable bearing. 70

24. In a switch-stand, a base comprising a front-to-rear shaft bearing at its front and a pedestal near its rear end, a lever with a shaft in said bearing, a pinion fixed on said shaft to the rear of said bearing, said shaft 75 having a recess centrally in its rear end, a pin extending through said pedestal forwardly into said shaft recess, a rack sliding on said pedestal and meshing with said pinion, a crank mounted on an upright axis on said base to the rear of said pedestal and extending forwardly and engaging with said rack, and locking means behind said pin, said crank lying against said locking means, thereby limiting backward displacement of 80 said pin from said shaft recess.

25. In a switch-stand, a base comprising a front-to-rear shaft bearing at its front and a pedestal near its rear end, a lever with a shaft in said bearing, a pinion fixed on said 90 shaft to the rear of said bearing, said shaft having a recess centrally in its rear end, a pin extending through said pedestal forwardly into said shaft recess, a rack sliding on said pedestal and meshing with said pinion, a crank mounted on an upright axis on 95 said base to the rear of said pedestal and extending forwardly and engaging with said rack, means to hold said rack down on said pedestal, said crank lying behind said pin 100 at the rear of said pedestal, and locking means retained by said crank against said pin and limiting backward displacement of said pin from said shaft recess.

26. In a switch-stand, a switch-throwing 105 pinion, a rack member meshing with said pinion, a support for said rack member, means fixed over and engaging said rack member and holding said rack member against said support, and bearings for said 110 pinion at both ends of said pinion, and switch-connecting means operatively connected to said rack member under said fixed means.

27. In a switch-stand, supporting means, 115 a rack member and a lever operatively mounted on said means, a pinion-segment coaxially connected to said lever, said rack member having a longitudinal inclined series of teeth and said pinion-segment having teeth to mesh with said rack teeth for throwing said rack member lengthwise, either one of two of said pinion-segment teeth engaging with corresponding rack teeth at either end of the rack member 120 throw nearer the center of said pinion-segment than teeth of said pinion-segment meshing with said rack teeth nearer the middle of the throw, and means to operatively connect said rack member to a switch. 125 130

28. In a switch-stand, a support, manipulating means, switch-connecting means, and mechanism permanently connected with said manipulating means to variably transmit motion of said switch-connecting means to said manipulating means, or to variably transmit motion of said manipulating means to said switch-connecting means.
29. In a switch-stand, a support, manipulating means, switch-connecting means, and mechanism comprising variable-radius rotary means, permanently connected with said manipulating means to variably transmit motion of said switch-connecting means to said manipulating means, or to variably transmit motion of said manipulating means to said switch-connecting means.
30. In a switch-stand, a support, manipulating means, switch-connecting means, and mechanism to transmit motion of said manipulating means to said switch-connecting means, comprising contact elements remote from each other and intermediate contact elements acting with different leverage than the leverage of said remote contact elements.
31. In a switch-stand, a support, manipulating means, switch-connecting means, and mechanism to transmit motion of said manipulating means to said switch-connecting means, comprising contact elements remote from each other and intermediate contact elements acting with less leverage from said manipulating means to said switch-connecting means than the leverage of said remote contact elements.
32. In a switch-stand, a support, manipulating means, switch-connecting means, mechanism comprising rotary means with contact elements remote from each other and intermediate contact elements farther from the center of rotation than said remote contact elements, to variably transmit motion of said manipulating means to said switch-connecting means or variably transmit motion of said switch-connecting means to said manipulating means.
33. In a switch-stand, a support, manipulating means, switch-connecting means, and mechanism to transmit motion of said manipulating means to said switch-connecting means having increased leverage to restrain said switch-connecting means at either end of the switch-throwing operation to a greater extent than in an intermediate part of said operation.
34. In a switch-stand, a pinion segment comprising a series of teeth the terminal ones of which are nearer the pinion rotation center than the intermediate ones.
35. In a switch-stand, a substantially semi-elliptical pinion segment.
36. In a switch-stand, a substantially semi-elliptical pinion segment having as its substantially median radius the major axis of the ellipse.
37. In a switch-stand, a substantially semi-elliptical pinion segment, and a rack having a curved series of teeth to mesh with the pinion segment teeth.
38. In a switch-stand, a substantially semi-elliptical pinion segment having as its substantially median radius the major axis of the ellipse, and a rack having a curved series of teeth to mesh with the pinion segment teeth.
39. In a switch-stand, in combination with a movable part of said switch-stand, leverage means contacting with said movable part to hold the switch-stand in switch-closing condition, but reducing its switch-holding leverage and increasing the degree of movement of said movable part incident to manual switch-opening movement of said leverage means.
40. In a switch-stand, switch-holding leverage means reducing its switch-holding leverage and increasing the degree of switch-opening operation by manual switch-throwing operation of said switch-stand.
41. In a switch-stand, switch-holding leverage means reducing its switch-holding leverage and increasing the degree of switch-opening operation incident to beginning of manual switch-throwing operation of said switch-stand, and increasing its switch-holding leverage and decreasing the degree of switch-opening operation incident to the ending of said operation.
42. In a switch-stand, a support, switch-connecting means swinging through a suitable switch-throwing angle, manipulating means swinging through substantially twice said switch-throwing angle, leverage means swinging directly with said switch-connecting means, leverage means swinging directly with said manipulating means and having substantially less than forty-six one-hundredths of the radius of said leverage means swinging with said switch-connecting means, and intermediate operatively connecting means whereby said switch-connecting means and said manipulating means swing each other throughout their respective angles.

FRANK C. ANDERSON.
